FILLING FEELER MECHANISM

John Rinne, Brooklyn, and Robert G. Mallard,
Staten Island, N. Y., assignors to The M. W.
Kellogg Company, New York, N. Y., a corpora-
tion of Delaware

Application November 8, 1946, Serial No. 708,638

8 Claims. (Cl. 139—286)

1

The present invention relates to a loomfeeler mechanism of the type which is responsive to a nearly exhausted condition of a bobbin for actuating the replenishing mechanism of an automatic loom.

The conventional type of mechanical loomfeeler mechanism comprises a comparatively long spring-pressed feeler arm mounted for pivotal movement and rigidly carrying a feeler tip which comes into engagement with the bobbin during the beat-up movement of the lay, and which is tiltably movable sidewise through a wide arc, as a result of the long leverage afforded by said arm. So long as the feeler tip engages yarn on the bobbin, it is restrained against sidewise movement along said bobbin by the friction between said tip and the comparatively soft mass of yarn. In order to assure against a false or premature indicating movement of the feeler tip, said tip is provided with a serrated or roughened yarn engaging or feeler surface. When the bobbin is nearly exhaustion, and the feeler tip finds a bare portion of the bobbin during beat-up movement, said tip slips along said bobbin portion, thereby tilting the feeler arm into actuating engagement with the transmission or connecting rod of a mechanism by which the exhausted bobbin is automatically replenished by a fresh bobbin.

With the conventional feeler mechanism described, any wide slippage of the tip along the yarn or any excessive pressure of said tip against said yarn will cause the sharp or roughened yarn engaging surface of said tip to cut into, catch or abrade the filaments or strands of said yarn, especially if it is of a delicate nature, such as rayon.

Furthermore, in a conventional feeler mechanism of the general type described, substantially the same part of the roughened tip is presented to the bobbin, both when the bobbin has an ample supply of yarn and when it is in nearly exhausted condition to initiate replenishment, so that substantial frictional resistance to sidewise slipping of the tip is undesirably encountered during its engagement with the nearly exhausted bobbin. This delays initiation of the replenishing operation.

Also, in a conventional feeler mechanism of the general type described, as the feeler arm is tilted through the engagement of the tip with a bare portion of the bobbin, resistance to this movement is progressively increased. The feeler mechanism is therefore not always sensitive, positive or certain in operation.

One object of the present invention is to provide a new and improved loomfeeler mechanism which

2

is certain, positive, sensitive and quick in operation, and which has a minimum of abrasive or other injurious effect on the yarn of the bobbin being detected.

Various other objects of the invention will be apparent from the following particular description, and from an inspection of the accompanying drawings, in which:

Fig. 1 is a horizontal section of a feeler mechanism embodying the present invention and shown in connection with a yarn filled bobbin, at the instant when said bobbin is first contacting the feeler tip during the beat-up movement of the lay;

Fig. 2 is a side elevation of the feeler mechanism in the phase of operation shown in Fig. 1, parts of the side wall of the case of said mechanism being shown broken away to expose the interior of said case;

Fig. 3 is a plan view of the feeler mechanism shown in connection with a yarn filled bobbin near the end of the beat-up movement of the lay, the cover of the feeler case being shown broken away to expose the interior of said case;

Fig. 4 is a plan view of the feeler mechanism, but shown in connection with a bobbin which has neared exhaustion, and which is at the limit of the beat-up movement of the lay, the cover of the feeler case being shown broken away to expose the interior thereof; and

Fig. 5 shows the plan view of a modified form of feeler tip which may be used in connection with the feeler mechanism of the present invention.

Referring to the drawings, there is shown a bobbin 10 which is mounted in a shuttle (not shown) of usual construction, and which carries the filling yarn A. The shuttle is picked back and forth along the lay (not shown) to form picks of the filling yarn in the shed. When the filling supply on the bobbin 10 is substantially exhausted, the bobbin is automatically ejected from the shuttle, and replaced by a fresh bobbin from a magazine through the operation of a replenishing mechanism. The shuttle is provided with the usual slot in its forward wall registering with an opening in the front wall of the shuttle box on the feeler loomside to permit the insertion of the feeler tip into contact with the bobbin as said bobbin is moved forwardly during beat-up movement of the lay.

The feeler mechanism of the present invention comprises a horizontal feeler case or housing 11 secured to a fixed part of the loom on one side thereof, as for example, by means of a bracket 12, and spaced in front of the shuttle picking

course. The case 11 is shown comprising a substantially rectangular box 13 having a top cover 14 removably secured thereto, as for example, by means of studs 15 threaded into nuts 16 welded to or otherwise secured to the inner face of the bottom wall of said box.

Axially slidable with a close slide fit in the end walls of the case 11 is a feeler arm or rod 17 having its rear section projecting out of said case and pivotally carrying at its rear projecting end a feeler tip 20 through a pivot mounting 21. The tip 20 is of thin case-like construction, and comprises a pair of opposed flat side walls 22 defining a recess 23 therebetween, and an outer end wall 24 between said side walls bevelled along its sides 19 towards its outer end, and presenting an outer convexly curved or arcuate feeler surface 25. The feeler rod 17 extends into the tip recess 23, and is formed at its rear end with an eye 26 through which a rivet pivot stud 27 extends to form the pivot mounting 21.

One end section 30 of the feeler surface 25 defines the yarn engaging portion of said surface, while the other section 31 of said surface defines the portion which slides into contact with the bare portion of the bobbin 10 when said bobbin is nearly exhausted and in condition for initiating the replenishing operation, as will be more fully described.

The rod 17 is urged axially outwardly and rearwardly towards the bobbin 10 with respect to the case 11 by a coil spring 35 encircling the case enclosed portion of said rod, and abutting at one end against a spring adjusting slide plate 36 in said case. The other end of the spring 35 bears against a collar 37 fixed to the rod 17 in the case 11.

Pivotally secured to the tip 20 by a pivotal mounting 38 is an indicator rod 40 passing through an elongated guide slot 41 in the rear wall of the case 11, and passing loosely through a pivot guide hole 42 in the front wall of said case. The indicator rod 40 also passes with clearance through a hole 43 in the spring adjusting slide plate 36, and is normally maintained parallel to the feeler rod 17.

To locate the pivot mounting 38 close to the axis of the rod 17 in inoperative position of the tip 20 shown in Fig. 1, the indicator rod 40 is angularly offset at its outer end 44 towards said axis. The offset rod end 44, extends into the tip recess 23, is flattened, and is apertured to receive a rivet pivot stud 45 forming part of the pivotal mounting 38.

For normally maintaining the feeler tip 20 in the inoperative position shown in Fig. 1, the indicator rod 40 has in the case 11 an encircling coil spring 50, which is weaker than the spring 35. The spring 50 bears at one end against a collar 51 fixed to the rod 40, and at its other end against an offset shoulder 52 formed at one end of a Z-shaped connector 53, and which is apertured to permit said rod to pass therethrough with a clearance fit. The other end of the connector 53 has an offset shoulder 54 through which the feeler rod 17 loosely extends with a clearance fit, and through which the pressure of the spring 35 is transmitted to the collar 37 on said rod. The aperture connections between the shoulder ends 52 and 54 of the connector 53 and the rods 17 and 40 respectively, afford enough play to permit relative slide movements between said shoulder ends and said rods, and to permit the rod 40 to be tilted from the inoperative position shown in Fig. 1 in which it is parallel to the feeler rod

17, to the tilted indicating position shown in Fig. 4, for initiating the operation of the replenishing mechanism.

The tension on the spring 35 may be adjusted through the plate 36. To that end, the plate 36 is threaded on a screw 55 journalled near one end in the front wall of the case 11, and near the other end in a bracket 56 fixed to one of the side walls of said case. The screw 55 has a knurled head 57 outside the case 11 readily accessible for manipulation, and has a threaded engagement with the adjusting plate 36, so that upon rotation of said screw, said plate slides in the case 11, and accordingly varies the extent of compression of the coil spring 35.

A connecting or transmission rod 60 has a slide bearing in a bracket 61 forming a rearward extension of one of the side walls of the case 11, and has one end 62 exposed and in the path of tilting movement of the indicator rod 40. At the other end, the connecting rod is spring-pressed towards the feeler mechanism, and is connected to a mechanism which initiates the replenishing operation. This mechanism may be of any suitable conventional type well-known in the art, or may be of the improved form shown in copending application, Serial No. 706,826, filed Oct. 31, 1946, now Patent No. 2,443,401, June 15, 1948.

To limit angular movement of the feeler tip 20 and in turn the rod 40 from the inoperative position shown in Fig. 1 to the indicating position shown in Fig. 4, there is provided a stop pin 63 connected to the side walls 22 of the feeler tip and adapted to engage the outer edge of the offset section 44 of the indicator rod 40 in extreme tilted position of said rod shown in Fig. 4.

In the operation of the feeler mechanism, the rod 17 is normally urged rearwardly towards the picking course of the bobbin 10 by the spring 35, and this spring pressure in turn is transmitted to the indicator rod 40 endwise thereof through the connector 53 and the coil spring 50 so that the two pivotal connections 21 and 38 will be relatively located with the connection 38 rearwardly of the connection 21 and close to the axis or line of action of the feeler rod 17. In the inoperative position of the feeler mechanism, the yarn engaging section 30 of the feeler surface 25 extends in the most rearward position of the feeler mechanism closest to the bobbin 10.

The inoperative position of the feeler mechanism shown in Fig. 1 is limited either by the stressed condition of the springs 35 and 50, by the engagement of the collars 37 and 51 against the rear wall of the case 11, or by the engagement of the inner edge of the offset end section 44 of the indicator rod 40 with the edge of the eye 26 of the feeler rod 17.

As a bobbin 10 having an ample supply of yarn A moves forwardly through the beating-up movement of the lay, the end section 30 of the feeler surface 25 being nearest to said bobbin will come in contact with said yarn. This causes the feeler surface section 30 to be indented into the relatively soft mass of yarn, so that substantial frictional contact is established between said feeler surface section and said yarn. Under these conditions, the force of the spring-pressed rod 17 in conjunction with the pushing force of the forwardly advancing bobbin produces a moment tending to rotate the feeler tip 20 clockwise about the pivot mounting 21. The length of lever arm of this moment is the distance between the axis or line of action of the feeler rod 17 and the con-

tact section of the tip 20 with the bobbin 10. This moment in the clockwise direction on the other hand is resisted by the friction force resulting from the contact of the feeler tip 20 with the yarn of the bobbin 10, this frictional resistance force having a lever arm extending between the pivot mounting 21 and the outer peripheral section of the yarn A.

The feeler surface 25 has a comparatively wide radius, so that as it is pressed into the relatively soft yarn A, the contact areas defined between said surface and said yarn are large, and the resulting friction force is sufficiently large to effectively resist clockwise rotation of the tip 20.

As the yarn laden bobbin 10 moves from initial contacting position (Fig. 1) towards its extreme forward position shown in Fig. 3, the feeler tip 20 is also moved with it, and held against rotation as described, so that the indicator rod 40 is maintained parallel to the feeler rod 17, and the connecting rod 60 is thereby not actuated.

After the filling supply A is unwound from the bobbin 10 sufficiently to expose its barrel or stem 61, as shown in Fig. 4, on the next beat-up stroke of the lay, the bare barrel will engage the tip 20. The bare barrel 61 being relatively hard and smooth, the friction force resisting rotation of the tip 20 clockwise about the pivot mounting 21 is reduced sufficiently to permit said tip to rotate in this direction. As the tip 20 is so rotated, its feeler surface 25 rides in slide contact over the denuded section of the bobbin barrel 61 from the yarn engaging section 30 of said feeler surface 25 to the bare bobbin engaging section 31. As the feeler tip 20 is rotated clockwise, the pivot mounting 38 for the indicator rod 40 moves transversely away from the axis of the rod 17, causing thereby the indicator rod 40 to tilt clockwise in the position shown in Fig. 4. Also, as this tip 20 is so rotated clockwise, the pivotal mounting 21 moves closer to the surface of the bobbin barrel 61, so that the lever arm of the friction force at the contacting areas of the feeler tip 20 and the bobbin barrel 61 will be progressively reduced, thereby progressively reducing resistance to the clockwise rotation of the tip about the pivot mounting 21. As a result of this progressively decreasing resistance to the clockwise turning of the feeler tip 20, the tip is snapped almost instantly and forcefully into position to actuate the connecting rod 60, once the rotation of said tip has been initiated by its engagement with the bare portion of the bobbin 10. This forceful snap action of the feeler tip 20 is desirable, especially since the connecting rod 60 is under comparatively strong spring pressure at its end opposite to the end 62.

The bobbin 10 in feeler actuating condition shown in Fig. 4 still carries a bunch of filling yarn at one end which is sufficient to provide filling thread for the weaving operation which occurs subsequent to the slipping of the feeler tip 20, but prior to the replacement of the spent bobbin with a fresh one.

It should be noted that the contact between the tip feeler surface 25 and the bobbin 10 is substantially confined to the same restricted area of said bobbin, both in yarn engaging condition of the feeler tip 20 and in bare bobbin engaging condition shown in Fig. 4, so that the bobbin engaging section of the feeler tip does not slide to any substantial extent along the length of the bobbin. Therefore, there is no slide action of the filler tip 20 that might cut, abrade or otherwise injure a wrap or two of the yarn on the bobbin.

Furthermore, the feeler tip 20 is so designed

and operated, that upon feeler contact with a bare section of the bobbin 10, the yarn engaging section 30 of the feeler tip surface 25 immediately rides past engagement with said bare bobbin section, while the other bobbin engaging surface section 31 of the tip progressively moves into slide contact with said bobbin. This is advantageous, especially in case it is found necessary to roughen or serrate the yarn engaging section 30 of the tip surface 25. This is not necessary, and the surface 25 is desirably made of uniform, somewhat smooth character, as shown in Figs. 1-4. If it is found necessary or desirable to increase the friction hold of the yarn on the tip, only the restricted yarn engaging section 30a of the tip surface 25a need be roughened or provided with teeth, while the remainder 31a of the tip surface remains smooth, as shown in Fig. 5. During actuating slide movement of the tip 20a, therefore, minimum of frictional resistance is offered to said movement.

Since the end 62 of the connecting rod 60 is exposed to full view, and not confined in the feeler case as in the conventional feeler mechanism, the adjustment of the position of said rod end with respect to the actuator rod 40 can be easily made.

The feeler rod 17 is confined to axial movement and is subjected to little or no bending stress during operations. The rod 17, therefore, will not wear quickly, and will not quickly wear the case 11, thereby increasing the serviceable life of the feeler mechanism.

As many changes can be made in the above mechanism, and many apparently widely different embodiments of this invention can be made without departing from the scope of the claims, it is intended that all matter contained in the above description or shown in the accompanying drawings shall be interpreted as illustrative and not in a limiting sense.

What is claimed is:

1. A loom feeler mechanism, comprising a thin case-like feeler tip having opposite side walls defining a recess therebetween, and having an outer end wall presenting a convexly curved feeler surface, a feeler arm for supporting said tip extending at one end into said tip recess, and having a pivot mounting at said end for said tip, and means responsive to the rotation of said tip about said pivot mounting for initiating a replenishing operation.

2. A loom feeler mechanism comprising a thin case-like feeler tip having opposite side walls defining a recess therebetween and having an outer end wall presenting a convexly curved feeler surface, a feeler arm for supporting said tip extending at one end into said tip recess and having a pivot mounting at said end for said tip, an indicator arm having one end extending into said tip recess and pivotally connected thereto at a section of said tip spaced from said pivot mounting, means guiding said indicator arm for angular movement upon rotation of said tip about said pivot mounting, and means responsive to the rotation of said tip about said pivot mounting for initiating a replenishing operation.

3. A feeler mechanism for a loom bobbin comprising, a support member, a feeler arm mounted on said support member for reciprocatory movement, means for urging said feeler arm toward the path of the bobbin, a feeler tip mounted adjacent one end thereof on said arm for bobbin exhaustion indicating pivotal movement and having an outer arcuate cam surface adapted to contact the bobbin, and means normally positioning

said feeler tip with a section adjacent the other end thereof of said surface disposed for initial contact with the bobbin, said cam surface being so shaped that the locus of contact between said surface and said bobbin remains substantially constantly positioned along said bobbin as said feeler tip goes through said indicating pivotal movement.

4. A feeler mechanism for a loom bobbin comprising, a support member, a feeler arm mounted on said support member for reciprocating movement, means for urging said feeler arm toward the path of the bobbin, a feeler tip mounted adjacent one end thereof on said arm for pivotal bobbin exhaustion indicating movement and having an outer arcuate cam surface adapted to contact the bobbin, and means normally positioning said feeler tip with a section adjacent the other end thereof of said surface disposed for initial contact with the bobbin, said initial contact section being roughened for yarn engagement, the remainder of said surface being smooth for engaging the bare portion of the bobbin, said surface being so shaped that the locus of contact between said surface and said bobbin remains substantially constantly positioned along said bobbin as said feeler tip moves through said indicating pivotal movement.

5. A feeler mechanism for a loom bobbin comprising, a feeler arm, means mounting said arm for longitudinal reciprocation with one end thereof facing the bobbin path, means urging said arm toward said bobbin path, an elongated feeler tip having one end pivotally supported on said one end of said arm, means urging said feeler tip into position to initially contact the bobbin with a section thereof adjacent its other end, said feeler tip including an arcuate bobbin contacting cam surface shaped to contact a single narrow region of the bobbin during the entire pivotal bobbin exhaustion indicating movement of said tip, whereby the moment arms of the forces applied to said tip by said feeler arm and the bobbin, tending to rotate said feeler tip about its pivotal support, are substantially constant throughout said indicating movement, and the moment arm of the friction restraining said pivotal indicating movement progressively diminishes during said movement.

6. A feeler mechanism for a loom bobbin comprising, a feeler arm, means mounting said arm for longitudinal reciprocation, means urging one end of said arm toward the bobbin path, an elongated feeler tip having one end pivotally supported on said one end of said arm, said feeler tip including an arcuate bobbin contacting surface shaped to contact a single narrow region of the bobbin throughout the exhausted bobbin indicating movement of said feeler about its pivotal support, an indicating arm pivoted to said feeler tip at a section thereof between the said pivotal support of said tip and the zone of said surface initially presented to contact with the bobbin, and means effective through said indicating arm urging said tip into initial bobbin contacting position, the pivot point of said indicating arm being substantially in line with said zone of initial contact and the pivot point of said feeler arm, whereby the moment arm of the force applied by said indicating arm progressively varies from a maximum on one side of said contact region to a maximum on the other side of said contact region as said feeler tip pivots through its exhausted bobbin indicating movement.

7. A feeler mechanism for a loom bobbin comprising, a support having front and rear end

members, a feeler arm mounted for straight line reciprocating movement in said support and extending through said members, an indicating arm mounted in said support adjacent said feeler arm for endwise movement and extending through said members, an elongated feeler tip pivoted adjacent one end thereof to the rear end of said feeler arm and having a bobbin contacting surface shaped to maintain the locus of contact between said surface and said bobbin substantially constantly positioned along said bobbin, the rear end of said indicator arm being pivoted to said feeler tip adjacent the other end thereof, a spring about said feeler arm having one end fixed relative thereto, a connecting member having one end engaging said one end of said feeler arm spring and having the other end engaging the other end of said indicating arm spring, said feeler arm spring being stronger than said indicating arm spring, said springs urging their respective arms toward the bobbin path and said feeler tip toward initial bobbin contact position, the pivot point of said indicator arm in said initial position being substantially in line with the pivot point of said feeler tip and the portion of said surface initially contacting said bobbin.

8. A feeler mechanism for a loom bobbin comprising, a case having front and rear ends, a feeler arm mounted for straight line reciprocating movement in said case and extending through said ends, a spring about said feeler arm having one end fixed relative thereto and urging said feeler arm toward the bobbin path, an adjustment piece in said case member having a hole therein through which said feeler arm passes, the other end of said spring bearing against said adjustment piece, means for moving said piece along said feeler arm to adjust the tension of said spring, an indicating arm mounted for straight line and for angular movement in said case member and extending through said ends, a second spring weaker than said first spring surrounding said indicator arm and having one end affixed relative thereto, a Z-shaped connecting member having one end mounted on said feeler arm and contacting said one end of said feeler spring and having its other end mounted on said indicator arm and contacting the other end of said indicating arm spring, said indicator spring urging said indicator arm toward initial bobbin contact position, and an elongated feeler tip pivoted adjacent one end thereof on the rear end of said feeler arm, the rear end of said indicator arm being pivoted to said tip adjacent the other end thereof, the pivot point of said indicator arm being substantially in line with the pivot point of said feeler tip and the original zone of contact between said tip and the bobbin.
